UNITED STATES PATENT OFFICE.

HARRIET R. TRACY, OF NEW YORK, N. Y., ASSIGNOR TO BENJAMIN T. BABBITT, OF SAME PLACE.

AUTOMATIC ELEVATOR-HATCH.

SPECIFICATION forming part of Letters Patent No. 253,323, dated February 7, 1882.

Application filed June 3, 1881. (No model.)

To all whom it may concern:

Be it known that I, HARRIET R. TRACY, of New York city, county of New York, and State of New York, have invented certain new and useful Improvements in Automatic Elevator-Hatches, of which the following is a full, clear, and exact description, reference being had to the accompanying drawings, and to the letters of reference marked thereon.

10 My invention has relation to that class of devices employed for closing the hatchways in elevator-shafts; and it consists essentially in the employment of a double series of vertically-moving hatches or doors, (one above and 15 the other below the car or carriage,) the two series being connected by suitable cords, chains, cables, or ropes, and so arranged that upon movement of the car or carriage up or down the hatchways will be successively closed; and 20 the invention involves, also, certain novel and useful arrangements or combinations of parts, details of construction, and peculiarities of operation, all of which will be hereinafter first fully described, and then pointed out in the 25 claims.

In the accompanying drawings I have chosen the ordinary shaft of a passenger-elevator with which to illustrate my improvements; but it is to be understood that the improvements are 30 applicable in connection with any form of car or carriage, whether for passengers, freight, or for other uses, the same being made movable within a shaft which it is desired to keep closed against upward drafts of air and 35 cured against accidental falling of persons and things.

In Figure 1 of the drawings I have shown a vertical section of an elevator-shaft having my improved hatches arranged to work there- 40 in in connection with the car or platform, the platform being shown as stopped at the lower floor, the hatchways above being closed by the hatches. Fig. 2 is a similar view, wherein the car is stopped at the upper landing. In both 45 these figures the movable hatches are connected with the bottom or adjacent part of the car by suitable attachments, being compelled to rise with the car as the latter ascends, and permitted to descend by reason of their grav-

ity as the car descends. Figs. 3 and 4 are 50 vertical sections, showing the two series of hatches united by endless ropes or cables, and adapted to be raised and lowered by mechanism independent of the car.

In all the figures like letters of reference, 55 wherever they occur, indicate corresponding parts.

It is well known that in buildings where elevators are employed the shaft wherein the car moves up and down operates as a chimney, in 60 which, in case of fire, the upward draft accelerates the combustion, and the chimney so formed facilitates the progress or passage of fire from one floor to the other. Serious accidents frequently occur to persons in the building where the hatchways are not closed as the car passes, and it is desirable to prevent the 65 possibility of persons or things falling down the shaft or well. The devices herein shown are well calculated to obviate these disadvantages, and their simplicity, cheapness, and easy working will commend them for adoption 70 in situations where needed.

A is the car, carriage, or platform, made to move up and down within the elevator-shaft, 75 which may be of any height and have any number of landings.

B' B² B³ are the hatches or doors above the car, intended to close the hatchways at the several landings when the car is at the lower- 80 most floor.

C' C² C³ are the hatches below the car, intended to close the hatchways at the several landings when the car is stopped at the upper floor. An inspection of the drawings will 85 show that by the arrangement adopted when the car is at any intermediate landing the hatchways above and below will be closed, and thus at all times the shaft be closed as the car passes either up or down.

As indicated in Figs. 1 and 2, the bands, 90 ropes, or cables D, which govern the motions of the hatches, are attached to the lowermost of the upper series of hatches, pass through the remaining hatches above the car, thence over a wheel or pulley, E, located at some convenient point in the upper part of the shaft, then down and around a lower wheel or pulley, F,

up through the lower series of hatches, and are then connected with the bottom of the car, or with some convenient point of the car. At suitable intervals on the hatch-ropes D 5 are the blocks or stop a' a'' a''' , arranged to pass freely over the wheel or pulley F, and to engage with the lower hatches in their order. For this purpose the blocks or stops are of varying size and pass through varying-sized openings in the hatches, or some other simple and convenient arrangement may be adopted for the purpose of making the connection with the hatches and their ropes at the proper intervals. As the car ascends from its position in Fig. 1 15 the block a' carries with it the hatch C', so that when the car has reached the second landing C' will close the opening at the first floor, and upon further upward movement of the car block a'' carries C² to the first floor, C' being further elevated and made to close the next opening, and so on for all the hatches below the car. As the car ascends of course the hatch B' is carried up by cable D. When B' strikes B² then both are carried up until the third is reached, and so on for all above the car. The car having reached the position indicated in Fig. 2, as soon as it commences to descend the hatches above and below descend with it, those above being arrested at their proper landings 25 by suitable stops, as b b , located upon the walls of the shaft, and those below being maintained upon the blocks attached to ropes D in a manner easily understood. A suitable ledge, d, may be provided in the lower part of the shaft for sustaining the lower series of hatches when 30 at their lowermost position.

Any suitable number of hatch ropes or cables D may be provided, according to the size and character of the hatches. The hatches are suitably notched, so as to pass the stops not intended to hold them in a manner easily understood.

The several hatches may, if desired, be counterbalanced, or a counterbalancing-weight may 45 be applied to the ropes or cables D.

Any convenient arrangement of the ropes or cables D may be made; but it is preferred to locate one portion of them exteriorly to the shaft, as indicated, so as to be entirely out of 50 the way of the car.

The hatches are intended to be made as light as is consistent with the uses for which they are intended, and a very light cable-connection for them will answer all the required purposes.

55 The improved hatches and attachments may be easily and cheaply applied to any of the forms of elevators now in use without material alteration of any parts, and without requiring skilled labor, as is necessary in connection with 60 some complicated forms of hatchway-covers which have been proposed.

Under some circumstances it may be desirable that the hatches be not moved by direct connection with the car, but by some independent mechanism. To provide for this 65 I make the ropes or cables D endless, sub-

stantially as indicated in Figs. 3 and 4. Instead of being attached to the bottom of the car, as in Figs. 1 and 2, they continue from the lower series of hatches up to the upper series. Under this arrangement the lower wheels may be driven by any suitable connection, as the shaft G and band-wheel H, with the engine or motor which moves the car, or they may be driven by an entirely independent 75 motor.

The operation of closing the hatchways is substantially the same as explained when referring to Figs. 1 and 2.

In many classes of elevators, particularly 80 those intended for carrying passengers, it is desirable that a space above the car be provided for light and ventilation, and to prevent the hatches above the car from coming too close down upon the roof of the car I provide a stop, I, on the elevator-cable, which may be moved up or down to any desired place, and will regulate the distance between the top of the car and the first hatch-cover above. This may be adjusted at pleasure, so 85 that at some times one distance between the car and hatch is maintained and at other times another distance.

With the endless ropes or bands and the stop I it will appear that the several hatches 90 may be moved upwardly without the use of the lower connections, if desired, the stop I serving, through the medium of the lowermost of the upper hatches, to move all the others at the proper time. They will descend by 95 their own gravity and assume their proper places, according to the position of the car, at any time.

The counter-balance may be applied to the endless ropes or bands in the same manner as 100 above explained.

Having now fully described my invention, what I claim as new, and desire to secure by Letters Patent, is—

1. In an elevator-shaft, the two series of 110 vertically-moving hatches, one above and the other below the car, adapted to close the openings in each floor as the car passes either up or down, the two series being connected by a chain or cable passing over suitable pulleys in 115 the region of the top and bottom of the shaft, substantially as and for the purposes set forth.

2. In an elevator-shaft, the two series of 120 vertically-moving hatches, one above and the other below the car, adapted to close the openings in each floor as the car passes either up or down, the two series being connected by a suitable chain or cable passing over pulleys or wheels, said chain or cable being provided with blocks or stops which determine the location and movement of the hatches in the lower series, substantially as shown and described.

3. In an elevator-shaft, the two series of 125 vertically-moving hatches connected by an endless band or cable having suitable stops or blocks, and running over suitable wheels or pulleys in the region of the top and bottom

of the shaft, substantially as shown and described.

4. In an elevator-shaft, the two series of vertically-moving hatches connected by an endless band or cable having suitable stops or blocks, and running over upper and lower pulleys, as explained, the two series being unconnected with the car, and capable of being operated in the manner and for the purposes set forth.

5. In combination with the hatch above the

car connected with those below the car by a suitable chain or cable, the adjustable stop located upon the elevator-cable, as and for the purposes set forth.

In testimony that I claim the foregoing I have hereunto set my hand in the presence of two witnesses.

HARRIET RUTH TRACY.

Witnesses:

JOHN BUCKLER,
WORTH OSGOOD.
